(57) **CLAIM**

We claim the ornamental design for a cable locking clip, as shown.

DESCRIPTION

FIG. 1 is an upper perspective view of the cable locking clip showing our new design attached to a connector that is shown in phantom lines;

FIG. 2 is a lower perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

The broken lines in the Figures are for illustrative purposes only and form no part of the claimed design.
